UNITED STATES PATENT OFFICE.

HARRY HIGHAM, OF MAPLEWOOD, NEW JERSEY, ASSIGNOR TO FRANK KREMENTZ COMPANY, OF NEWARK, NEW JERSEY, A CORPORATION OF NEW JERSEY.

DESIGN FOR AN OPHTHALMIC MOUNTING.

Application filed November 17, 1927. Serial No. 24,195. Term of patent 3½ years.

To all whom it may concern:

Be it known that I, HARRY HIGHAM, a citizen of the United States, residing in Maplewood, county of Essex, and State of New Jersey, have invented a new, original, and ornamental Design for Ophthalmic Mountings, of which the following is a specification, reference being had to the accompanying drawing, forming a part thereof.

In the drawing,

Figure 1 represents a front view of an ophthalmic mounting, showing my new design.

Figure 2 represents an enlarged fragmentary perspective view of a portion of said mounting.

I claim:

The ornamental design for an ophthalmic mounting as shown.

HARRY HIGHAM.
